UNITED STATES PATENT OFFICE.

AUGUSTUS J. EAVES, OF OSSINING, NEW YORK, ASSIGNOR TO WESTERN ELECTRIC COMPANY, INCORPORATED, OF NEW YORK, N. Y., A CORPORATION OF NEW YORK.

IMPEDANCE-CHANGING DEVICE.

Application filed August 9, 1923. Serial No. 656,563.

This invention relates to artificial lines and more particularly to artificial line adjusting devices for controlling a plurality of impedance elements.

5 An object of the invention is the provision of an impedance varying device which is simple and efficient and which may be operated in a facile and expeditious manner to balance the impedance of a transmission line.

10 According to the preferred form, the invention provides an impedance adjusting device which comprises a switch for varying the resistance, and means for varying the electrostatic capacity in an artificial line.

15 The switch consists of a plurality of equally spaced banks of contacts with a contact arm for each bank arranged to engage the contacts for progressively changing the impedance in a circuit, in the order of the 20 arrangement of the banks of contact. Each bank of contacts is staggered with respect to the other banks of contacts so that the contacts in the banks will be engaged by the contact arms with respect to the contacts in 25 the other banks successively, thereby increasing the total number of possible changes in the associated resistance, for one complete rotation.

In the drawing, Fig. 1 illustrates a switching device of the invention partly in cross-section; Fig. 2 is a sectional view taken 30 along the broken line 2-2 of Fig. 1; and Fig. 3 illustrates the invention as applied to a duplex telegraph system.

35 A better understanding of the invention may be had from the following description, taken in conjunction with the accompanying drawing, wherein one embodiment of the invention is illustrated.

40 Referring now for the moment to Fig. 1, a switching device is shown which comprises a plurality of circular blocks of micarta, or other suitable insulating material, 5, 6 and 7, which have, as shown in Fig. 2, a plurality of equally spaced apertures 8.

45 Through these apertures extend clamping bolts 9, 10 and 11, which serve to securely hold the various circular blocks in position to the panel or other supporting means 12.

50 In order that the circular blocks will be spaced properly, sleeves 13 surrounding the bolts 9, 10 and 11 between the panel 12 and the block 5 and between the other blocks are provided. Thus, by drawing down the nuts 55 individual to the clamping bolts, the switch

structure may be securely clamped in place. Each of the circular blocks 5, 6 and 7 also has a central aperture through which a rotatable shaft 16 extends. This shaft 16 is divided into a plurality of sections, one individual to each of the circular blocks 5, 6 and 7. For securing the respective sections of the shaft to one another, collars 17 are provided, each of the collars being fixedly secured in any suitable manner to one of the adjacent sections of the shaft and arranged to lock itself to the other of the adjacent sections by means of suitable keys 14. Also secured to the shaft 16 is a dial and knob 18 serving as a means for rotating the 70 shaft.

Rigidly fastened on each section of the shaft are U-shaped contact arms 19 which are made up of a plurality of flat springs and which are held in position by means of clamping nut 20. One end of the contact arm 19 engages the flat surface of a plurality of L-shaped contact pieces 21, which, as shown in Fig. 2, are equally spaced in the blocks 5, 6 and 7. The other end of the 80 contact arm 19 rests on a hub 22 of conducting material, which has a terminal 23 serving as a connecting means for the next section of the resistance. These brushes are of such width as to bridge two adjacent contact pieces on their respectively associated blocks before an existing connection with a contact is opened, the purpose of this arrangement being to maintain a continuous connection 85 during the rotation of the brushes. 90

It is to be noted that in each of the circular blocks 5, 6 and 7 the sets of apertures 8 are arranged equi-distant around the outside circumference and as shown in the drawing there are preferably three sets, each of which are, therefore, spaced on centers of 120°. The sets consist of three apertures each and are arranged to be substantially in alignment with the corresponding sets on the three blocks, with the exception that the first aperture of any set in block 5 is in perfect alignment with the second aperture of its corresponding set in block 6 and with the third aperture of its corresponding set in block 7 and are securely held in their respective relative positions by the bolts 9, 10 and 11. This arrangement provides a means for successively varying the resistance in the artificial line in the order of the positions of the blocks. Thus, inasmuch as the contact 100 105 110

segments 21 are equally spaced in their respective blocks and the contact arms 19 bear the same angular position, engagement thereof with the conducting segments will be such that when the brush on block 5 is centered on a contact, as shown in Fig. 3 of the drawing, the brush on block 6 will span the contact corresponding to that in engagement on block 5 and the succeeding contact, and the brush on block 7 will be centered on the contact corresponding to the said succeeding contact on block 6 or what is designated on block 5 as 21. It is thus seen that such a switching device makes it possible to combine in a single unit, switch structures which may be operated from a common element successively. By having eleven conducting segments in each bank and there being three banks in the case illustrated, the number of steps for a complete rotation will be thirty-three.

Referring now to Fig. 3, there is shown a telegraph line 25 which terminates in a pair of ratio arms 26 and 27, to the apex of which there is connected the usual transmitting equipment 28. Bridged across the apex of the ratio arms 26 and 27 is a receiving relay 29 which responds only to incoming impulses. Connected to the junction point between the relay 29 and the ratio arm 27 is an artificial line, which consists of a plurality of resistances 30, 31 and 32, a resistance 33 and two variable condensers 34 and 35. As is customary in duplex signaling resistance 33 and condenser 34 seem to balance the nearby portions of the line. Each of the resistances 30, 31 and 32 is connected to a contact segment 21 individual to the circular blocks 5, 6 and 7. As shown in this figure, the contact arm 19 for the contacts arranged in the circular block 5 is in engagement with segment 21', while the contact arm 19 individual to the circular block 6 is bridging the corresponding segment with the succeeding one or that corresponding to 21' on block 5, while the contact arm 19 for the block 7 is centered on the contact corresponding to 21. It is thus apparent that the present invention provides a switching device whereby for a single movement the resistance may be varied in steps successively. It is to be understood, however, that the artificial line comprises a plurality of such resistances, the resistances for the other steps being of either higher or smaller values to give the required adjustment. The condenser 35 is connected between the resistances for the sections 5 and 6 and so connected that this condenser which balances the more distant capacity of the line is always at one third of the resistance connected in the circuit, thus giving a more accurate adjustment. Also as the resistance is increased the distance which the condenser 35 is from the line is automatically changed.

Although the invention has been disclosed and described with reference to a particular type of system, it is obvious that modifications may be made without departing from the spirit and scope of the present invention. 70

The invention claimed is:

1. In an impedance changing device, a plurality of banks of impedance elements, and means for changing the impedance successively in the order of the arrangement 75 of the banks.

2. In an impedance changing device, a plurality of banks of resistance elements, a capacity element located at approximately one-third the total resistance, and means for 80 changing the resistance successively in the order of the banks and automatically maintaining the position of the capacity element at approximately one-third of the total resistance. 85

3. In an impedance changing device, a plurality of banks of equally spaced conducting segments, each of said banks being disposed on an offset with respect to the other banks, impedance elements connected 90 to said conducting segments, and means for successively engaging the segments in each of the banks for successively changing the impedance in the order of the arrangement 95 of the banks of impedances. 95

4. An artificial line simulating the impedance of an actual line, an impedance changing device in said artificial line comprising a plurality of banks of resistance elements, a capacity element, and means for changing in a single movement said resistance elements successively in the order of the banks so as to balance the impedance of said artificial line with that of said actual line and means to maintain an approximately fixed ratio between the resistance and the capacity elements. 100

5. An artificial line simulating the impedance of an actual loaded line, an impedance changing device in said artificial 110 line comprising a plurality of banks of resistance elements, a capacity element, and common means under unitary control for varying the said resistance elements and automatically maintaining said capacity element located at approximately one-third of the balancing resistance. 115

6. An artificial line simulating the impedance of an actual loaded line, an impedance changing device in said artificial 120 line comprising a plurality of banks of resistance elements, an adjustable capacity element, and means for changing the resistance successively in the order of the banks and automatically shifting the position of the adjustable capacity element in the artificial line to maintain it at approximately one-third of the total resistance of the artificial line. 125

7. An artificial line simulating the char- 130

acteristic impedance of an actual loaded line, an impedance adjusting device in said artificial line comprising a plurality of banks of equally spaced conducting segments arranged in a circle, each of said banks being offset with respect to the other banks, resistance elements connected to said conducting segments, an adjustable capacity element, and means for successively engaging 10 the segments in each of the banks for suc-

cessively changing the resistance in the order of the arrangement of the banks of resistances and automatically shifting the position of the capacity element to maintain it at approximately one-third of the total resistance of the artificial line. 15

In witness whereof, I hereunto subscribe my name this 6th day of August A. D., 1923.

AUGUSTUS J. EAVES.
